Primary Examiner — Darcey E Gottschalk*Assistant Examiner* — Haley K Schnebele(74) *Attorney, Agent, or Firm* — TILLMAN WRIGHT, PLLC(57) **CLAIM**

The ornamental design for insulation for packaging as shown and described.

DESCRIPTION

FIG. 1 is a top rear left orthogonal view of insulation for packaging.

FIG. 2 is a bottom rear right orthogonal view of the insulation for packaging of FIG. 1.

FIG. 3 is a front plan view of the insulation for packaging of FIG. 1.

FIG. 4 is a left plan view of the insulation for packaging of FIG. 1.

FIG. 5 is a rear plan view of the insulation for packaging of FIG. 1; and,

FIG. 6 is a right plan view of the insulation for packaging of FIG. 1.

The broken lines in the drawings are for the purpose of illustrating environmental structure and defining bounds of the claimed design and form no part of the claimed design. The claim is limited to the solid lines and shaded surfaces.

1 Claim, 3 Drawing Sheets
